UNITED STATES PATENT OFFICE.

JOSEF GMEINDL, SR., JOSEF GMEINDL, JR., JOHANN GMEINDL, AND ALOIS GMEINDL,
OF ED, POST SCHNAITSEE, NEAR GARS, GERMANY.

DEVICE FOR CHARGING FURNACES.

1,007,861.

Specification of Letters Patent.

Patented Nov. 7, 1911.

Application filed January 4, 1910. Serial No. 536,299.

To all whom it may concern:

Be it known that we, JOSEF GMEINDL, Sr., JOSEF GMEINDL, Jr., JOHANN GMEINDL, and ALOIS GMEINDL, citizens of Germany, residing at Ed, Post Schnaitsee, near Gars am Inn, Bavaria, Germany, have invented certain new and useful Improvements in Devices for Charging Furnaces; and we do hereby declare the following to be a full, clear, and exact description of the invention, such as will enable others skilled in the art to which it appertains to make and use the same.

Devices for charging furnaces, in which cell-wheels connected with checks are set in motion by the weight of the fuel fed into the cells, are a part of the prior art. In order to enable such a device to feed a certain amount of fuel at given intervals into the furnace the present invention provides a tipping double-receptacle below the cell-wheel, which receptacle is so arranged in bearings that it can be adjusted to empty at desired intervals.

The preferred embodiment of the invention is illustratively exemplified in the accompanying drawing, wherein—

Figure 1 is a vertical sectional view of the device looking at one side thereof; and Fig. 2 is a similar view at right angles to Fig. 1, looking at the front of the device.

Below the feed-funnel *a* a cell-wheel *b* of known construction is arranged, connected by pinion gear or the like with a check *c* of any suitable type. Thus the cell-wheel *b* is rotated in the direction of the arrow by the fuel fed into it. Below the cell-wheel *b* is arranged a tipping double receptacle *d*, consisting of two vessels or receptacles arranged diametrically opposite to one another on an axis *f*, pivoted in spring carried bearings *h*. This double receptacle *d* is arranged unsymmetrically below a feed funnel in such a manner, that the upper vessel when charged will always have the tendency to tip over, from doing which it is however prevented by an adjustable pin *g*, until such time as the weight of the fuel in the vessel acting against the supporting springs of the bearings *h* causes the vessel to sink below said pin *g*. In this manner the (for the time being) uppermost receptacle will always, as soon as sufficiently full of fuel, tip over and empty its contents into the charging funnel below and at the same time the

other vessel will be turned up to receive a fresh charge, being in its turn held in position by the pin *g* and the friction spring-arm *i*.

The furnace charging funnel below the tipping receptacle *d* connects with a conduit *l*, having an automatic valve *m*, fitted with side-pieces *n*, overlapped by the pieces *o* connected to the funnel side. The flow of fuel to the cell-wheel can be regulated by any means adapted to the purpose, and as a variety of devices for such regulation are in common use it has not been deemed necessary to illustrate the same in detail. The quantity of each charge can be regulated by adjusting the pin *g*. It may also be mentioned that this feeding contrivance may also be used for purposes other than charging a furnace without in any way departing from the essential idea of the invention.

What we claim as our invention and desire to secure by Letters Patent is:

1. In furnace charging apparatus, the combination with a fuel feeding hopper, of a rotary wheel having pockets for receiving fuel from the hopper, a tipping receptacle to which the fuel is fed from the said wheel, spring supported bearings in which said tipping receptacle is yieldingly carried, and an adjustable unyielding stop projecting into the path of said tipping receptacle, whereby the tipping receptacle may be regulated to tip under the weight of different quantities of fuel entering the same.

2. In furnace charging apparatus, the combination with a fuel feeding hopper, of a rotary wheel having pockets for receiving fuel from the hopper, a tipping receptacle revolvably mounted below said wheel and adapted to receive fuel from the same, means for preventing reverse rotation of said tipping receptacle, spring supported bearings in which said tipping receptacle is yieldingly carried, and an unyielding stop projecting into the path of rotation of said receptacle, said stop being adjustable to have a greater or less portion of its length project into the path of said receptacle whereby the latter may be regulated to tip under the weight of different quantities of fuel entering the same.

3. In furnace charging apparatus, the combination with a fuel feeding hopper, of a rotary wheel having pockets for receiving fuel from the hopper, a tipping receptacle

below said wheel and adapted to receive fuel therefrom, unyielding means projecting into the path of said receptacle whereby the latter may be regulated to tip under varying weights, a conduit for receiving fuel from said receptacle, and an automatic valve in said conduit comprising side members *n*, and members *o* overlapping said side members.

10 In testimony whereof we hereunto affix

our signatures in the presence of two witnesses.

JOSEF GMEINDL, SEN.
JOSEF GMEINDL, JR.
JOHANN GMEINDL.
ALOIS GMEINDL.
